[57] CLAIM

The ornamental design for the front face of a vehicle wheel, as shown and described.

DESCRIPTION

FIG. 1 is a perspective view of the front face of a vehicle wheel according to the present invention; and,

FIG. 2 is a front elevational view of the front face of a vehicle wheel, as shown in FIG. 1.

The broken line showing of environmental structure in the drawing is for illustrative purposes only and forms no part of the claimed design.
